REFACING TOOL

Michael P. Schlosser, Byram, Conn.

Application December 9, 1947, Serial No. 790,548

12 Claims. (Cl. 51—241)

1

This invention relates to a refacing tool.

It is an object of the present invention to provide a refacing tool adapted to be extended over a shaft projecting from a housing to effect upon the end of a projected bushing through which the shaft is extended a smooth face with which the sealing ring of an oiltight seal surrounding the shaft engages for oiltight contact.

It is another object of the present invention to provide a refacing tool for compressors used on refrigerators wherein a new face can be placed on the bushing extended through the compressor housing without having to disassemble the compressor other than removing the motor which drives the same therefrom.

It is another object of the present invention to provide in a refacing tool for the end faces of shaft bushings adequate support for the tool which may be connected to the shaft to serve as an extension and wherein there will be provided automatic spring pressure for maintaining the abrasive upon the bushing while the same is rotated on the shaft extension and wherein this spring pressure may be adjusted by a simple and easily operated adjusting means.

Other objects of the present invention are to provide a refacing tool for refacing the ends of shaft bushings without having to disassemble the enclosing structure, which is of simple construction, inexpensive to manufacture, easy to install and efficient in operation.

For other objects and for a better understanding of the invention, reference may be had to the following detailed description taken in connection with the accompanying drawing, in which

Fig. 1 is a collective side elevational view of the motor seal displaced from the shaft of a compressor and of the tool embodying the features of the present invention connected to the shaft for operation upon the shaft bushing with portions broken away to show the interior of the same.

Fig. 2 is a fragmentary perspective view of the shaft extension of the form of the invention shown in Fig. 1.

Figs. 3 and 4 are respectively slightly different forms of the shaft extension.

Fig. 5 is a perspective view of the locking ring adapted to fit the shaft extensions shown in Figs. 2, 3 and 4.

Fig. 6 is a side elevational view of a still further form of the tool, in which the shaft extension is locked to the shaft, the Allen screw being used for this purpose, the same as the form shown in Fig. 1.

2

Fig. 7 is a side elevational view of another form of the invention with portions broken away and shown in section of the tool which is connected directly to the shaft and may be used only when the compressor or other structure of which the shaft is a part has been disassembled for access to the end of the shaft in order to permit the removal of the tool.

Fig. 8 is a perspective view of one of the abrasive elements.

Fig. 9 is a fragmentary and sectional view of a modified form of the invention.

Referring now to Fig. 1, 15 represents a compressor such as used on certain refrigerators and which has a pump rotor 16 with a shaft 17 which extends outwardly through a bushing 18 in a cover plate 19. The bushing 18 has its end extending beyond the face of the cover plate and provides a surface for an oil seal device 21 having a ring member 22 with a face 23 adapted to have sealing engagement with the end face of the bushing 18. This seal 21 has a flexible housing forming a part thereof to cover the shaft and a portion 24 adapted to be threaded upon the threaded end of the shaft 17 as shown at 25. The member 24 has a flange 26 with pins 27 extending therefrom to have driving engagement with openings on a coupling flange of an electric motor which drives the compressor. The face 23 of the seal often becomes worn and the seal is removed from the shaft for the purpose of resurfacing the same. This can be done by rubbing the ring face 23 on emery cloth resting on a flat surface. The end face of the bushing 18 is more difficult to resurface. To effect this operation without having to disassemble the compressor and while in place on the refrigerator, the electric motor and the seal 21 are removed from the shaft 17. My tool is then connected to the shaft 17 and upon rotating the same a new surface is placed on the bushing 18.

The tool, according to the form shown in Fig. 1, includes a shaft extension 28 which is internally threaded and hollow throughout. This extension 45 is applied to the threaded end 25 of the shaft 17 and is locked in place thereon by an Allen screw 29. The outer end of the extension 28 is knurled as shown at 31 to facilitate the threading of the same upon the shaft portion 25. With the extension 28 locked in place, the same will serve as a support for a rotatable holder 32. This holder has on its inner end a washer of abrasive paper or cloth. This washer is indicated at 33. The washer is retained by a retaining sleeve 34. The 50 washer will engage with the end of the bushing 65

and as the rotary member 32 is rotated, the end of the bushing will be refaced.

In order to provide a pressure urging the emery cloth toward the end of the bushing, the outer end of the sleeve is provided with a groove 35 adapted to receive a pin 36 of a retainer 31. The retainer ring 37, when arranged so that the pin 36 is located in the grooves 35, will serve as a stop for a pressure spring 38 surrounding the extension 28 and acting upon the rotor body 32. It will be noted that one or more pins 36 are located in the ring 37 offset from the center. The purpose of this is to permit the retainer to be adjusted or inverted so that a different spring tension will be applied to the rotor body. As viewed in Fig. 2, 15 there are one or more longitudinal grooves 41 to permit the pins 36 to be extended to the grooves 35. In order to provide for additional adjustment or for a different location of the ring 37 on the sleeve 28 in order to give a further variation of the spring pressures, there are provided two or more grooves 42 and 43, as shown in Fig. 3. Longitudinal grooves 44 will permit the projection 36 to be adjusted along the extension and enter the grooves 42 or 43. In order to prevent the ring 37 from becoming angularly displaced when it is in use in such a manner as would release the same from the extension 28 and notches 45 are provided in the edge of the grooves for receiving the pin 36.

In Fig. 4, it will be noted that there is shown a spiral groove 48, about which the pin 36 can be rotated to locate the ring 37 at different distances along the sleeve 28. Longitudinal grooves 49 are provided for receiving the pin and likewise there are notches 51 for retaining the ring 37 at the differently angled locations.

In Fig. 6, there is shown another form of the invention utilizing an internally threaded sleeve 52 adapted to be secured to the threaded end 25 of the shaft 17. This screw is locked in place by an Allen screw 53. Rotatably mounted on this sleeve 52 is a rotary member 54 on which is axially adjustable, a washer retaining member 55 having a washer 33 and a retaining ring 56 for securing the washer to the member 55. This member 55 is axially adjustable on the rotary member 54 and this axial movement is limited by a stop screw 57 which may engage opposite ends of an elongated slot 58 in the member 54. A spring 59 surrounds the member 54 and acts between a shoulder 61 and the outer end of the member 55 whereby to urge the member 55 toward the bushing face when the tool is mounted on the shaft 17.

In order to vary the tension of the spring 59, the sleeve 52 is provided with threads 62. On the thread portion 62 are lock nuts 63 and 64. The lock nuts can be adjusted to any position along the thread portion 62 whereby to position the member 54 at a different location on the sleeve 52 so as to alter the tension of the spring 59.

In operation, the extensions are first fixed to the shaft 17 and then locked with the screws against displacement therefrom. Thereafter the rotary members are disposed on the extensions for angular adjustment to effect the refacing operation by the engagement of the abrasive with the end of the bushing. It will be apparent that with this arrangement of an extension that the tool can be easily released from the shaft upon disassembling the same. The shaft itself can be held while turning the extension from the same.

In Fig. 7 there is shown a form of the invention which is adaptable where the compressor has

been disassembled and access can be had to the rotary part thereof in rear of the cover 19. In this form, there is an abrasive retaining member 76 on which is fixed abrasive 77 by a retainer ring 78. This member 76 is mounted for axial adjustment on a handle or rotary member 79. This member 79 has a threaded opening 81 for receiving the threaded portion 25 of the shaft 17. The member 79 has a large knob portion 82 by which it can be turned. A spring 83 is disposed on the member 79 between the knob portion and engages with the outer end of the retainer. A stop screw 84 acting in slot 85 limits the inward and outward movement of the retainer member 76 on the member 79. In this tool there are less parts but once the tool has been assembled on the shaft, it is necessary that the rotor body 16 of the shaft be retained in order to loosen the tool from the shaft.

In Fig. 9 there is shown a still further form of the invention in that the ring with the pin projection is dispensed with. A pin 87 is placed directly in the rotary member 88 and a groove 89 is located in the shaft extension 91 closer to the inner end of the same. A pin 92 is extended through the extension 91 to lock the extension on the shaft 17. The rotary member 88 is placed on the extension 91 by sliding the same thereonto by aligning the pin projection 87 with a groove 93 on the extension 91 and thereafter when the pin 87 has arrived in the groove 89 rotating the same so as to lock with any one of the notches 94. The notches 94 are of different length in order to provide for a different adjustment of the spring surrounding the rotary member.

It should be apparent that there has been provided a locking device for round members on which there is to be disposed a rotary member to be adjusted thereon, a simple and easily connected and adjusted lock device. Such lock device can have application on ordinary bolts to retain a nut in place or upon a shaft having a driving rotary element.

While various changes may be made in the detail construction, it shall be understood that such changes shall be within the spirit and scope of the present invention as defined by the appended claims.

I claim:

1. A refacing tool for refacing the end of a bushing having a shaft extending therethrough, comprising a member adapted to be secured to the shaft, an abrasive retaining member axially adjustable on said member, and spring biasing means extending between the member and the abrasive retainer to urge the abrasive retainer toward the end of the bushing while the parts are being rotated to reface the same.

2. A refacing tool for refacing the end of a bushing having a shaft extending therethrough, comprising a member adapted to be secured to the shaft, an abrasive retaining member axially adjustable on said member, and spring biasing means extending between the member and the abrasive retainer to urge the abrasive retainer toward the end of the bushing while the parts are being rotated to reface the same, and a pin and slot connection between the member and the retainer for limiting the axial movement of the retainer on the member.

3. A refacing tool for refacing the end of a bushing having a shaft extending therethrough, comprising a member adapted to be secured to the shaft, an abrasive retaining member axially adjustable on said member, and spring biasing means extending between the member and the retainer for refacing the end of the bushing.

abrasive retainer to urge the abrasive retainer toward the end of the bushing while the parts are being rotated to reface the same, and means on said member and acting against the abrasive retainer to adjust the spring tension.

4. A refacing tool adapted to reface the end of a bushing through which a shaft is extended, the shaft having a threaded portion, an extension adapted to be connected to the threaded portion of the shaft, a locking screw for fixing the extension to the shaft, an abrasive retaining member rotatably adjustable on the shaft extension, spring retainer means on the extension, a spring extending between the spring retainer and the abrasive retainer.

5. A refacing tool adapted to reface the end of a bushing through which a shaft is extended, the shaft having a threaded portion, an extension adapted to be connected to the threaded portion of the shaft, a locking screw for fixing the extension to the shaft, an abrasive retaining member rotatably adjustable on the shaft extension, a spring retainer on the extension, a spring extending between the spring retainer and the abrasive retainer, said spring retainer having a pin projection, said extension having an annular groove and a longitudinal groove connected therewith to permit the passage of the pin projection of the spring retainer to the groove for locking engagement therewith when angled from the longitudinal groove.

6. A refacing tool as defined in claim 5 and said pin projection being offset from the center of the spring retainer whereby the spring retainer may be inverted and applied to the extension in a different position to alter the spring tension.

7. A refacing tool as defined in claim 5 and said extension having a plurality of grooves adapted to receive the pin projection of the spring retainer and the grooves being longitudinally spaced from one another on the extension, longitudinal grooves leading to the annular grooves to permit the passage of the projection thereto.

8. A refacing tool as defined in claim 4 and said spring retainer means having an inwardly extending pin projection, said extension having a spiral groove adapted to receive the pin projections of the spring retainer and longitudinal grooves extending along the extension from one section of the groove to another, and said groove having notches in the side thereof adapted to receive the pins at the angled positions of the spring retainer on the extension.

9. A locking arrangement comprising a round member having an annular groove therein and

a longitudinally extending slot extending from one end of the member to the groove, a locking member adapted to be extended over the round member and having a pin projection extending inwardly therefrom and adapted to pass through the longitudinal groove of the round member to the annular groove thereof and to be rotated for locking engagement with the groove.

10. A locking arrangement comprising a round member having an annular groove therein and a longitudinally extending slot extending from one end of the member to the groove, a locking member adapted to be extended over the round member and having a pin projection extending inwardly therefrom and adapted to pass through the longitudinal groove of the round member to the annular groove thereof and to be rotated for locking engagement with the groove, and said groove having in one side thereof a notch for the pin to retain the locking member against rotational displacement.

11. A locking arrangement comprising a round member having an annular groove therein and a longitudinally extending slot extending from one end of the member to the groove, a locking member adapted to be extended over the round member and having a pin projection extending inwardly therefrom and adapted to pass through the longitudinal groove of the round member to the annular groove thereof and to be rotated for locking engagement with the groove, and said pin extending from said member in an offset position from the center thereof and adapted to enter the groove when the rotary member is extended onto the round member in a reverse manner whereby to provide for a different adjustment of the locking member upon the round member.

12. A locking arrangement comprising a round member having a spiral groove therein and a longitudinally extending slot extending from one end of the member to the groove, a locking member adapted to be extended over the round member and having a pin projection extending inwardly therefrom and adapted to pass through the longitudinal groove of the round member to the spiral groove thereof and to be rotated for locking engagement with the groove, said spiral groove being continuous for more than one turn, and said groove having notches in the side thereof for receiving the pin to retain it against angular displacement.
